UNITED STATES PATENT OFFICE.

WILLIAM H. ALBERT, OF HARTFORD CITY, INDIANA, ASSIGNOR TO CHARLES O. FLEMING, OF HARTFORD CITY, INDIANA.

WEANING-BIT.

1,188,366.

Specification of Letters Patent. Patented June 20, 1916.

Application filed October 16, 1915. Serial No. 56,255.

To all whom it may concern:

Be it known that I, WILLIAM H. ALBERT, a citizen of the United States, residing at Hartford City, in the county of Blackford 5 and State of Indiana, have invented certain new and useful Improvements in Weaning-Bits, of which the following is a specification, reference being had to the accompanying drawings.

10 This invention has for its primary object a novel and useful construction of weaning bit for animals, the parts being so constructed and arranged that they may be very easily and cheaply manufactured and readily assembled and adjusted, according to the size of the animal's mouth.

15 A further object of the invention is a weaning bit which will permit the animal to drink without any discomfort and which 20 will at all times be kept in a sanitary condition. And the invention also aims to generally improve devices of this class so as to render them more useful and commercially desirable.

25 With these and other objects in view, as will more fully appear as the description proceeds, the invention consists in certain constructions, arrangements and combinations of the parts that I shall hereinafter 30 more fully describe and claim.

For a full understanding of the invention, reference is to be had to the following description and accompanying drawing, in which—

35 Figure 1 is a perspective view of my device as applied. Fig. 2 is an elevation thereof, and Fig. 3 is a sectional view showing the manner in which the bit may be varied in width, as required.

40 Corresponding and like parts are referred to in the following description and designated in all of the views of the accompanying drawing by like reference characters.

45 My improved bit comprises two curved tubular sections 1 and 2 open from end to end and secured together at one end in an adjustable manner, whereby the bit may be varied in size, according to the size of the animal's mouth to which it is applied. In

the present embodiment of the invention, the 50 tubular sections have a sleeve 3 secured thereto in any desired way, and each end of the sleeve 3 is interiorly threaded, as at 4, to receive the exteriorly threaded ends 5 of the sections. The cross bar of the bit which, 55 in the present instance, is formed by the adjoining ends of the tubular sections 1 and 2, and the intermediate sleeve 3, is formed with any desired number of orifices 6, these orifices being of any desired size and number, 60 there being three in the present instance, one in each of the tubular sections and one in the sleeve, although it is to be understood that the invention is not limited in this regard. In order to secure the bit in place and hold 65 it in the animal's mouth, each one of the sections is provided with loop straps 7, preferably of metal, soldered or otherwise secured thereto, and in each of the straps is a ring 8.

70 From the foregoing description in connection with the accompanying drawing, the operation and advantages of my improved weaning bit will be apparent. By having the parts adjustably connected together, the bit may be varied in size, as hereinbefore 75 stated, to fit the animal's mouth, and by having the bit hollow throughout with turned ends and with the orifices 6 above specified, the animal can drink without any discomfort, as the water may be sucked up 80 into the bit through both ends of the same, while at the same time the water passing through the bit, in the act of drinking, will cleanse the bit out and it will thus be maintained at all times in a thoroughly sanitary 85 condition.

While the accompanying drawing illustrates what I believe to be the preferred embodiment of my invention, it is to be understood that the invention is not limited thereto, but that various changes may be made in the details of construction, arrangement and proportions of the parts without departing from the scope of the invention as defined by the appended claims.

90 95 What is claimed, is:

1. A bit of the character described, comprising curved tubular sections, and means

for adjustably connecting said sections together, the cross bar of the bit being formed with orifices.

2. As a new article of manufacture, the 5 herein-described weaning bit, comprising complementary tubular sections, a sleeve adjustably connecting said sections together, the cross bar of the bit being formed with

orifices, and bridle or halter engaging rings secured to the bit.

In testimony whereof I hereunto affix my signature in the presence of two witnesses.

WILLIAM H. ALBERT.

Witnesses:

CARLETON A. WRIGHT,
ELMER R. TUTROW.
